UNITED STATES PATENT OFFICE.

WILLIAM P. DAVIES, OF BELLEVUE, KENTUCKY, ASSIGNOR TO EDNA B. DAVIES, OF BELLEVUE, KENTUCKY, AND GRACE I. BAINUM, OF CARTHAGE, OHIO.

MOUNTING FOR RAILROAD-RAILS.

1,075,200.

Specification of Letters Patent.

Patented Oct. 7, 1913.

Application filed August 11, 1913. Serial No. 784,126.

To all whom it may concern:

Be it known that I, WILLIAM P. DAVIES, of Bellevue, State of Kentucky, have invented certain new and useful Improvements in Mountings for Railroad-Rails; and I do hereby declare the following to be a full, clear, and exact description of the invention, such as will enable others skilled in the art to which it appertains to make and use the same.

This invention relates to improvements in mountings for railroad rails, such for example as stringers, ties and chairs,—the object of the invention being to provide a cushioning structure which shall be particularly applicable for use with or forming part of concrete ties or other foundation members and which shall operate to protect such concrete base members, as well also as the rolling equipment, from sudden hammering, shocks and strains which might tend to deteriorate the concrete foundation member or subject the rolling equipment to wear and rough usage.

With these and other objects in view, the invention consists in certain novel features of construction and combinations of parts as hereinafter set forth and pointed out in the claims.

In the accompanying drawings, Figures 1, 2 and 3 are views illustrating the application of my improvements to a railroad tie. Fig. 4 is a plan view showing the cushioning devices arranged longitudinally under the rails and transversely over the ties, and Figs. 5, 6, 7 and 8 are views illustrating the application of my improvements to a railroad chair.

1 represents a railroad tie constructed preferably of concrete and constituting a foundation member. Pneumatic cushioning devices are located upon the tie and are preferably made to extend approximately from end to end thereof. These cushioning devices comprise a base member 2 having depressed flanges 3 at its edges, and an upper or cap member 4 also having depressed flanges 5, at its edges, the cap member being made to telescope over the base member, 45 closely fitting the outer walls of the latter so as to effect air-tight connection, and forming an air cushion between said members 2 and 4. The concrete of the tie enters bottom of the base member 2 and the latter 50 is secured to the tie by vertical bolts 6 pass-

ing through the flange 3 and through the concrete tie,—said bolts also passing freely through holes in the flange 5 of the cap member 4 and provided with keys 7 to limit the upward movement of said cap member. The bolts 6 may also be provided with keys 8 under the tie. The cap member 4 serves to receive the rail 9 and suitable fastening means are provided on said cap member for securing the rail thereto. 60 A duct 11 is made in the tie and is open to the air at one end, the inner end of said duct being made to communicate with the air space 12 formed by and between the telescoping members 2 and 4. A strip of wood 70 or other yielding material 13 is placed loosely within the air chamber 12 and constitutes a valve for the port 14 of the duct 11. The upper cap member 4 of the cushioning devices is maintained normally in 75 and returned to its normal position, by means of a weighted lever 15,—said lever being pivotally supported at 16 and its short arm being made to engage under the rail, or a spring such as shown in Fig. 7 may be 80 employed, and weighted levers or springs may be located at both ends of the cushioning devices.

In the construction shown in Fig. 4, the cushioning devices are arranged transversely 85 over the ties as indicated at 17 and longitudinally under the rail,—two or more of the cushioning devices being arranged in line with each other under each rail section and spaced apart between adjacent ties. The 90 cushioning devices thus arranged produce, in effect, stringers for the rail and the weighted levers, such as indicated at 18, Fig. 4, may be located between the adjacent 95 ends of each two cushioning devices 17.

In Figs. 5, 6, 7 and 8, my improvements are shown applied to a railroad chair,—the concrete foundation member of which is indicated at 19. In other respects, the construction of the devices is the same as in 100 Figs. 1, 2 and 3, except that elliptical springs 20 are shown at each end of the cushioning devices 21, instead of weighted levers. It is evident however, that either springs or weighted levers may be employed for raising the cap member of the cushioning device, with any of the arrangements shown in the drawings.

With the use of my improvements, an air cushion will be maintained in the cushion-

ing devices which will absorb shocks and protect the concrete foundation members from the effects of hammering strains. If desired the ducts leading to air chambers of 5 a plurality of cushioning devices may be connected.

Various slight changes might be made in the details of construction of my invention without departing from the spirit thereof or 10 limiting its scope and hence I do not wish to restrict myself to the precise details herein set forth.

Having fully described my invention what I claim as new and desire to secure 15 by Letters-Patent is:—

1. The combination with a foundation member, of cushioning means for a rail thereon, said cushioning means comprising relatively movable members forming an air 20 chamber between them, means securing the lower member of the cushioning means to the foundation member, and means for supplying said air chamber with air.

2. The combination with a concrete foundation member, of cushioning means thereon, said cushioning means comprising telescoping members forming an air chamber between them, an air duct in the foundation member and communicating with said 30 air chamber, the upper member of said cushioning means adapted to support a rail, and yielding means for raising said upper member of said cushioning means.

3. The combination with a foundation member, of cushioning means mounted thereon, said cushioning means comprising relatively movable members forming an air chamber between them, a duct in the foundation member and communicating with 40 said air chamber, yielding means for raising the movable member of said cushioning means, and a strip mounted in the bottom of said air chamber and constituting a valve for said duct.

4. Cushioning means for railroad rails, 45 comprising relatively movable members forming an air chamber between them, means for securing the lower member to a foundation, means for supplying air to said air chamber, and yielding means for raising 50 the upper member.

5. Cushioning means for railroad rails, comprising relatively movable telescoping members forming an air chamber between them, means for rigidly securing the lower 55 member to a foundation, the upper member adapted to receive a rail, the lower member having an air inlet, a valve normally closing said inlet, and yielding means for raising the upper member. 60

6. The combination with a concrete base member, of cushioning means comprising relatively movable members forming an air chamber between them, the lower member of said cushioning means formed to receive a 65 portion of the concrete base member, means securing said lower member to the foundation member, an air duct communicating with the air chamber, a valve in said air chamber for said duct, and yielding means 70 for raising the upper member of said cushioning means.

7. The combination with a foundation, of rail cushioning means thereon, said rail cushioning means comprising relatively 75 movable members forming an air chamber between them, means for introducing air into said chamber, means for securing the lower member to the foundation, and a weighted lever operating to raise the upper member. 80

In testimony whereof, I have signed this specification in the presence of two subscribing witnesses.

WILLIAM P. DAVIES.
